UNITED STATES PATENT OFFICE.

REUBEN B. STIPES, JOHN D. GOODWIN, AND HOWARD C. WELCH, OF FLINT, MICHIGAN.

DESIGN FOR A WHEEL-HOLDER.

58,260.

Specification for Design. Patented June 28, 1921.

Application filed January 21, 1921. Serial No. 439,028. Term of patent 14 years.

To all whom it may concern:

Be it known that we, REUBEN B. STIPES, JOHN D. GOODWIN, and HOWARD C. WELCH, citizens of the United States, resident at Flint, in the county of Genesee, State of Michigan, have invented a new, original, and ornamental Design for a Wheel-Holder, of which the following is a specification, reference being had to the accompanying drawing, forming part thereof.

Figure 1 is a side elevation of the wheel holder showing our new design;

Fig. 2 is a plan of the same;

Fig. 3 is a view of the inner end of the wheel holder;

Fig. 4 is a view of the outer end of the same, and

Fig. 5 is a longitudinal sectional view of the wheel holder.

We claim:

The ornamental design for a wheel holder, as shown.

REUBEN B. STIPES.
JOHN D. GOODWIN.
HOWARD C. WELCH.
